UNITED STATES PATENT OFFICE.

JULIUS DREYFUSS, OF NEW YORK, N. Y.

DESIGN FOR TRIMMING.

SPECIFICATION forming part of Design No. 17,762, dated October 11, 1887.

Application filed May 7, 1887. Serial No. 237,488. Term of patent 3½ years.

To all whom it may concern:

Be it known that I, JULIUS DREYFUSS, a citizen of the United States, residing at New York, in the county and State of New York, have invented and produced a new and original Design for Trimmings, of which the following is a specification, reference being had to the accompanying drawings, forming part thereof.

Figure 1 is a plan view of my newly designed trimming fabric, and Fig. 2 is a section of the same, these views fully illustrating my design.

The object of my invention is to furnish a new and effective design for strips of trimming; and the leading feature of my design consists of three cords laid together, the central one being ornamented on its top edge with a line of beads.

Referring to the drawings, $a' a' a'$ represent three cords, the outer ones, $a' a'$, having a twist-like appearance, and the inner one a plain appearance, and having the bead-line b on its top edge.

What I claim as new, and desire to secure by Letters Patent, is—

The design for trimmings herein shown and described, composed of the cords $a' a'$, having a twist-like appearance, and cord a , having a line of beads, b , on its top edge, as set forth.

JULIUS DREYFUSS.
